DESIGN.

J. A. FERN.

PHONOGRAPH CASE.

APPLICATION FILED AUG. 6, 1920.

57,829.

Patented May 10, 1921.

John A. Fern INVENTOR
by John W. Trehli ATTORNEY.

UNITED STATES PATENT OFFICE.

JOHN A. FERN, OF CINCINNATI, OHIO.

DESIGN FOR A PHONOGRAPH-CASE.

57,829.

Specification for Design.

Patented May 10, 1921.

Application filed August 6, 1920. Serial No. 401,801. Term of patent 7 years.

To all whom it may concern:

Be it known that I, JOHN A. FERN, a citizen of the United States of America, and a resident of the city of Cincinnati, in the county of Hamilton and State of Ohio, have invented a new, original, and ornamental Design for a Phonograph-Case, of which the following is a specification, reference being had to the accompanying drawing, forming part thereof.

In the drawing,

The figure is an isometric view of a phonograph case, showing my new design.

I claim:

The ornamental design for a phonograph case, as shown.

Witness my hand at the city of Cincinnati, in the county of Hamilton and State of Ohio, this 31st day of July, 1920.

JOHN A. FERN.
